(57) **CLAIM**

The ornamental design for a sliding bar latch, as shown and described.

DESCRIPTION

FIG. 1 is a front elevation view of a sliding bar latch showing the new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a first perspective view thereof;

FIG. 8 is a second perspective view thereof; and,

FIG. 9 is a third perspective view of the sliding bar latch engaged on a bar.

The broken lines shown in the figures are for illustrative purposes only and form no part of the claimed design.
